WINDOW LOCK

William M. Blakely, Fort Bragg, N. C.

Application November 7, 1945, Serial No. 627,180

3 Claims. (Cl. 292—127)

1

This invention relates to improvements in fasteners or locks for window sashes or like closure elements, and particularly to a fastener or lock for holding a sash or closure element in closed position.

One object of the invention is to provide an improved fastener or lock which will automatically fasten or lock the sash or closure element at the final moment of the movement of the sash or closure element into closed position, thus ensuring the positive fastening of the sash or closure element as and whenever it is closed.

Another object of the invention is to provide a fastener or lock of this character which is simple of construction, reliable and efficient in action, and adapted to be manufactured and installed at a comparatively low cost.

Still another object of the invention is to provide a fastener of this character having improved manually operable releasing means including a member adapted to serve as a handle actuatable to release the fastener and to aid the operator in moving the sash to open position.

With these and other objects in view, which will appear in the course of the subjoined description, the invention consists of the novel features of construction, combination and arrangement of parts hereinafter fully described and claimed, and as shown in the accompanying drawings, in which:

Fig. 1 is a vertical transverse section of portions of a window frame and sash, in this instance a lower sash, showing the application of the invention thereto, with the sash fastened in closed position;

Fig. 2 is a horizontal section on the line 2—2 of Fig. 1 showing the latch in projected position;

Fig. 3 is a similar view showing the latch in retracted position;

Fig. 4 is a transverse section through the lower rail of the sash, taken on line 4—4 of Fig. 2;

Fig. 5 is a sectional elevation taken on line 5—5 of Fig. 1 looking toward the inner face of the stile of the window frame having the keeper recess therein;

Fig. 6 is a view of a portion of the lower rail of the sash looking toward the inner face thereof and showing the face plate with the guide slot therein;

Fig. 7 is a section on the line 7—7 of Fig. 8 through the stem of the fingerpiece;

Fig. 8 is a side elevation and Fig. 9 an end view of the stem of the fingerpiece.

Referring now more particularly to Figs. 1 to 9, inclusive, of the drawings, 1 designates a

side stile or jamb of a window frame or like frame having an opening therein, and 2 and 3, respectively, designate the bottom rail and one of the side rails of a window sash or like closure mounted to slide in the opening in the frame. In accordance with my invention the parting groove 4 of the stile 1 in which the sash rail 3 slides is formed at its lower end with a keeper recess 5 having an undercut socket 6 at its top and an underlying inner inclined or sloping wall portion 7.

Provided in the sash at the base of the side rail 3 is a mortise 8 communicating at its inner portion with a relatively smaller recess 9 which in turn communicates with a relatively smaller but longer recess 10 extending longitudinally within the adjacent end of the bottom rail 2. A latch 11 is pivotally mounted at its upper end, as at 12, within the mortise and has an upturned hook 13 at its lower end. The latch is thus mounted to swing out of and into the mortise for movement into and out of the recess 5 and the bill of its hook is adapted to engage the socket 6 to lock the sash in closed position. The bill of the hook 13 is rounded, as at 14, and the hook has a curved or inclined undersurface 15, for a purpose hereinafter described.

Mounted to slide, transversely of the sash, in the mortise 8 and recesses 9 and 10, and through backing and guide plates 16 and 17 engaging shoulders in the recesses, is a latch actuating rod 18. The latch is pivoted to the outer end of this rod, as at 19, and the rod is provided adjacent thereto with a flange or shoulder enlargement 20 movable between the mortise 8 and recess 9. A coiled spring 21 is disposed in the recess 9 between the plate 16 and shoulder 20 and acts to normally slide the rod outward and project the latch into locking position as shown in Fig. 1.

The rod 18 is formed with an inner portion 22 of reduced diameter to provide a stop shoulder 23. In this portion of the rod is an elongated slot 24 opening through opposite sides of the rod. The slot 24 communicates with a slot 25 formed in the inner side of the rail 2 and which is covered by a face plate 26 having a slot 27 arranged in alignment with the slot 24. An operating fingerpiece or handle 28 is arranged to bear against the face plate and has a stem 29 extending through and slidably mounted in the slots and provided with outer and inner oppositely projecting fork arms 30 and 31 lying on opposite sides of the portion 22 of the rod 18 and of its stem portion 29 which passes through the slot

24 in the rod, said arms being normally spaced from the shoulder 23. The sides of the outer ends of these arms which face the plate 17 are grooved to form seats 32 for the outer end of a coiled spring 33 encircling the rod portion 22 between said fork arms 30 and 31 and the plate 17. The function of this spring 33 is to maintain the fingerpiece in proper position for operation in and relative to the slots 24 and 27.

Figs. 1 and 2 and Fig. 3, respectively, show the locking and retracted positions of the latch, from which the working operations will be readily understood. When the sash is open and the latch retracted and the sash is being moved upward or downward the curved bill or toe of the latch 11 will ride on the face wall of the groove 4 whereby the latch will be held in a retracted position, but when the sash is moved downward to a closed position the latch will automatically snap into engagement with the keeper to positively lock the sash from upward movement. By reference to Figs. 1 and 2 it will be seen that outward movement of the bolt rod 18 to latch projecting position moves slot 24 outwardly and allows spring 33 to shift the stem 29 of the operating handle or fingerpiece 28 to bring the stem 29 into engagement with the inner end of slot 24 and outer end of slot 27 in the face plate 26 so that on subsequent inward sliding movement of the fingerpiece 28 positive motion against the inner end wall of slot 24 may be transmitted to slide the rod inwardly against the resistance of springs 21 and 33 to retract the latch 11 and withdrawing the rounded bill 14 of the hook 13 from the recess 5. This movement of the parts will swing the latch to its retracted position and shift the stem 29 from the outer to the inner end of slot 27 to allow free outward movement of the rod 18 when the latch is again brought into position to engage the keeper. When the latch is thus retracted by manual movement of the operating handle or fingerpiece 28 the sash will be released for free upward and downward movements to adjust it to any open position. Fig. 3 shows the position of the parts after the sash has been unlatched to permit movement to an open position by the operation of the fingerpiece or handle 28, and it will be apparent that as the latch rod 18 is moved inward or to the right from the position shown in Fig. 2 to the position shown in Fig. 3 in retracting the latch the outer wall of the slot 24 will be brought into engagement with the stem 29 of the handle member as said stem is shifted to the right in slot 27. This movement of the stem 29 causes the spring 33 to be compressed for a subsequent return action after release of the fingerpiece 28, at which time the latch will be projected by means of the spring 21 to shift the stem 29 and fingerpiece 28 to the left to the position shown in Figs. 1 and 2.

It will be observed from the foregoing that whenever the sash is lowered it will be automatically locked, preventing oversight or forgetfulness in locking a window, while at the same time it may be readily unlocked for raising. The same mechanism in reverse may be used for locking upper sashes instead of lower sashes, and the mechanism may also be used for locking other types of closures in closed position. In practice a fixed fingerpiece may be arranged on the sash adjacent to the fingerpiece 28 and to the right of the slot 27 to enable an operator to grasp both the fixed and movable fingerpieces with one hand and retain the same in lifting the sash, so that both hands may be used in operating the

sash as soon as the sash has been unlocked by retraction of the latch member from its keeper.

In order to protect the surface of the stile from injury by rubbing contact with the latch, a metallic wear plate 34 may be applied to the stile for running contact of the bill of the latch therewith. Also a guard plate 35, preferably carried by plate 34, may be arranged to close the space between the stile 1 and rail 3 at the outside of the window to prevent the introduction of a tool in surreptitious attempts to release the latch from the outside of the window. In addition to the fact that the improved lock herein described ensures the fastening of the sash each time it is closed, it will be seen that the applied lock presents no hooks or other surfaces difficult to manipulate or to catch clothing or collect dust.

From the foregoing description, taken in connection with the drawings, the construction, mode of operation and advantages of my improved fastener or lock will be readily understood and appreciated by those versed in the art without a further and extended description. It will be understood, of course, that while the structures shown herein are preferred changes in the form, construction and arrangement of parts, such as fall within the scope of the appended claims, may be made without departing from the spirit or sacrificing any of the advantages of the invention.

30 I claim:

1. For use with a sash frame having a side stile provided with a keeper, a sliding sash, a latch on the sash rail movable into and out of the plane of the sash to keeper disengaging and engaging positions, said latch being pivotally mounted in the sash and having a hook portion extending below the pivot point and engageable with the keeper when disposed in register therewith and adapted for running contact with the frame when out of register with the keeper to hold the latch retracted, a sliding rod within the sash pivoted to the latch below the first named pivot point, resilient means acting on the rod for projecting the latch into engagement with the keeper when coming into register therewith, manual means operable on the rod and slidable with reference to the sash for moving the latch out of engagement with the keeper, and resilient means for returning the manual rod operating means to normal position on release thereof.

2. For use with a sash frame having a side stile provided with a keeper, a sliding sash, a latch on the sash rail movable into and out of the plane of the sash to keeper disengaging and engaging positions, said latch being pivotally mounted in the sash and having a hooked end portion extending below the pivot point and engageable with the keeper when disposed in register therewith and adapted for running contact with the frame when out of register with the keeper to hold the latch retracted, a sliding rod mounted within the sash and pivoted to the latch below the first named pivot point, resilient means acting on the rod for projecting the latch into engagement with the keeper when coming into register therewith, a slideable fingerpiece operable on the rod for moving the latch out of engagement with the keeper, and resilient means acting on the fingerpiece to automatically return it to normal position on release thereof after actuation.

3. For use with a sash frame having a side stile provided with a keeper, a sliding sash, a latch on the sash rail movable into and out of the plane of the sash to keeper disengaging and engaging positions, said latch being pivotally mounted

within the sash and having a hooked end portion extending below the pivot point and engageable with the keeper when disposed in register therewith and adapted for running contact with the frame when out of register with the keeper to hold the latch retracted, a sliding rod slideable within the sash and pivoted at one end to the latch at a point intermediate the hooked portion and the point at which the latch is pivoted to the sash, resilient means acting on the rod for projecting the latch into engagement with the keeper when coming into register therewith, a slideable fingerpiece operable on the rod for moving the latch out of engagement with the keeper, and a spring acting on the fingerpiece to return it to a normal position after actuation.
